UNITED STATES PATENT OFFICE.

ROSS M. G. PHILLIPS, OF WEST HAVEN, CONNECTICUT, ASSIGNOR OF ONE-HALF TO IDA MOELLER PHILLIPS, OF WEST HAVEN, CONNECTICUT.

INCLUSIVE WATCH-HOLDER.

1,229,182.

Specification of Letters Patent.

Patented June 5, 1917.

Application filed July 15, 1916. Serial No. 109,554.

To all whom it may concern:

Be it known that I, Ross M. G. PHILLIPS, a citizen of the United States, residing at West Haven, in the county of New Haven 5 and State of Connecticut, have invented a new and useful Improvement in Inclusive Watch-Holders; and I do hereby declare the following, when taken in connection with the accompanying drawings and the 10 characters of reference marked thereon, to be a full, clear, and exact description of the same, and which said drawings constitute part of this application, and represent, in—

Figure 1 a view in front elevation of an 15 inclusive watch-holder constructed in accordance with my invention.

Fig. 2 a view thereof in vertical section on the line 2—2 of Fig. 1.

Fig. 3 a detached view in side elevation of 20 the base and locking-segments.

Fig. 4 a plan view thereof.

Fig. 5 a view in inside elevation of the removable shell.

Fig. 6 a view thereof in central section on 25 the line 6—6 of Fig. 5.

My invention relates to an improvement in watch-holders designed in particular for use on automobiles, but applicable for use in a variety of other situations, the object 30 being to produce a simple and convenient holder in which the entire watch is concealed except the face, whereby the watch is protected, and given the appearance of a miniature clock.

With these ends in view, my invention 35 consists in an inclusive watch-holder having certain details of construction as will be hereinafter described and pointed out in the claims.

In carrying out my invention, I employ 40 a removable cup-like metal shell 7 larger in diameter than the "over-all" diameter of the watch to be received by it, that is to say, larger in diameter than the watch 45 with its pendant and bow. The said shell 7 has a deep flange 8 at a right angle to its face 9 which is formed with an opening 10 corresponding in diameter to the diameter of the face of the watch to be 50 used, the edge of the opening 10 being slightly turned outward to form a centering-flange 11 to receive the bezel of the watch. To economize space, the opening 10 in the face 9 of the shell is arranged, as 55 shown, at one side of the center thereof. If

desired, however, the opening might be made concentric with the shell which would then have to be larger than strictly necessary. To the inside of the face 9 of the shell I attach a watch retaining-wire 12 secured in 60 place, as shown, by solder 13 and comprising an inwardly extending retaining-loop 14 for engagement with the back of the watch and a retaining-end 15 for engagement with the pendant of the watch, the said 65 loop 14 and end 15 being yielding and the end 15 having a bend 16 to fit over the pendant. The retaining-means 12 or its equivalent, positions the watch in the shell and holds its face against the flange 11 of the 70 shell and in registration with the opening 10 aforesaid.

The flange 8 of the shell is provided with inwardly extending locking-studs or pins 17 located diametrically opposite each other, 75 for engagement respectively with the tapering cam-like ends 18 of two yielding shell-centering and shell-locking segments 19 slightly smaller in curvature than the flange 8 of the shell, and secured at their butt ends 80 to arms 20 turned upward from the ends of a strap 21 attached by screws 22 to a circular base-plate 23 having screw-holes 24 by means of which it is fastened to the cowl-board or other part of an automobile. The 85 said segments 19 are separated from each other at their ends for the reception of the studs 17 which ultimately enter locking-notches 25 in their cam-like ends 18.

The watch 26 having been positioned in 90 the shell in front of the yielding loop 14 and end 15, the shell 7 is set over the segments 19 with its locking-studs 17 registered with the spaces between the ends thereof. The shell now centered by the said segments, is rotated for the engagement of the studs 17 with the ends 18 thereof. As soon as the studs 17 ride into the notches 25, the shell is firmly locked to the base 23 from which it can be detached only by reversely 100 rotating it sufficiently to ride the studs 17 out of the notches 25 and bring them into registration with the spaces between the ends of the segments after which the shell may be removed.

When the watch 26 is positioned within 105 the shell, it is entirely inclosed therein except as to its face and presents the appearance of a small clock. My improved holder is thus an inclusive holder in so far as it 110

takes in and protects the entire watch except its face.

I claim:

1. In a watch-holder, the combination with a base, of a concentric shell smaller in diameter than the said base but larger in diameter than the over-all diameter of the watch and formed with an opening for the exposure of the watch-face, yielding segments applied to the said base for centering the shell which fits over them, and means carried by the shell for engagement with the said segments, whereby the shell is removably attached to the base by its partial rotary movement with respect thereto.
2. In a watch-holder, the combination with a base, of a concentric shell smaller in diameter than the same but larger in diameter than the over-all diameter of the watch and

provided in its face with an opening for the exposure of the watch-face, means for removably connecting the shell with the base, and means carried by the shell for engaging with the back and pendant of the watch for positioning the same.

3. In a watch-holder, the combination with a base, of a concentric shell smaller in diameter than the said base, but larger in diameter than the over-all diameter of the watch and provided in its face with an opening for the exposure of the watch-face, a pair of yielding segments applied to the base in position to have the shell fit snugly over them, locking means carried by the shell for engaging with the said segments on the partial rotation of the shell, and means carried by the shell for positioning the watch.

ROSS M. G. PHILLIPS.
